(57) **CLAIM**

The ornamental design for a foldable mailer having a check component and an address correction component, as shown and described.

DESCRIPTION

FIG. 1 is a perspective view of a foldable mailer having a check component and an address correction component, the mailer shown in unfolded condition;

FIG. 2 is a back perspective view thereof;

FIG. 3 is front perspective view of the foldable mailer having the check component and the address correction component, the mailer shown in a folded condition; and,

FIG. 4 is a back perspective view thereof.

The broken lines represent physical perforations in the mailer. The portions of the disclosure shown in broken dash-double-dot lines represent structural environment and form no part of the claimed design.
